UNITED STATES PATENT OFFICE.

ALFRED TROSCH, OF ROCHESTER, NEW YORK, ASSIGNOR TO ARTHUR H. INGLE, OF ROCHESTER, NEW YORK.

SPEED-CONTROLLING MECHANISM FOR PLANERS.

Application filed March 18, 1921. Serial No. 453,472.

To all whom it may concern:

Be it known that I, ALFRED TROSCH, a citizen of the United States of America, residing at Rochester, in the county of Monroe 5 and State of New York, have invented certain new and useful Improvements in Speed-Controlling Mechanism for Planers, of which the following is a specification.

My invention relates to metal planers, and 10 has for its purpose to afford a practical and simple mechanism for controlling the speed of an electrically driven machine.

More particularly, the invention has to do 15 with the type of planer adapted for operating upon work at different points throughout the forward travel of the work support and driving the work support at a slow rate of speed during cutting operations and at a fast rate of speed between such cutting operations.

A further purpose of the improvement is 20 to provide a mechanism for electrically driven machines, in such a way that the work support is returned at a constant rate of speed, although making its forward travel 25 at variable speeds as already explained.

The invention also comprehends certain 30 other improvements and advantageous features as will appear from the following detailed description, in conjunction with the accompanying drawings, the novel features 35 being pointed out in the claims following the specification.

In the drawings:

Figure 1 is a side elevation of a planer, 40 equipped with a preferred embodiment of the invention.

Figure 2 is a similar view, enlarged and partially broken away.

Figure 3 is an end elevation, and

Figure 4 is a view similar to Figure 3, with the switch box adjusted to inoperative position.

In general, the invention comprises a resistance-controlling switch, governing a resistance element in the circuit of the motor operating the work support of the planer, and the switch is alternately moved back and forth during the forward travel of the 45 work support, but remains stationary during the return travel of the work support. This is preferably accomplished by providing the switch with horizontally extending operating portions located one above the other and 50 terminating in different vertical planes,

while the traveling work support carries devices such as pairs of adjustable dogs which cooperate with the operating portions of the switch. There are as many pairs of dogs as there are cutting periods, or slow speed periods, during the forward travel of the work support, and each pair includes a short downwardly extending dog of such length as to 60 cooperate with the uppermost operating portion on the switch, and a longer downwardly 65 extending dog of such length and so formed at its lower end as to cooperate with the lower operating portion on the switch. As the work support travels along, the shorter dog of a pair engaging the upper operating 70 portion moves the switch in one direction, while the longer dog of the pair cooperating with the lower operating portion of the switch returns the latter to its normal position. The distance between the dogs of each 75 pair represents the distance through which the work support travels at a slow speed for cutting, while the distance between one pair and the first dog of the next pair represents the distance through which the work support 80 travels at a fast rate of speed. During the return travel of the work support, the controlling dogs ride over the operating portions of the switch without affecting the position of the same. The switch box carrying 85 the switch, is preferably mounted upon the bed of the machine at a point underneath the traveling work support and in such manner as to be adjustable horizontally, so as to move the switch out of cooperating relationship 90 with the controlling dogs, when it is desired to drive the work support forwardly at a constant speed.

Referring now to the present disclosure which is intended to illustrate one example 95 of a practical embodiment of the invention, A designates the bed of the machine while B is the electrically driven work support or table traveling on the bed, these parts being of the usual form well known in the art of 100 metal planers, and it will be understood that the tool, mounted on a cross head above the work support, is omitted because unnecessary to a disclosure of the present invention.

Arranged beneath the work support B, 105 and attached to one side of the bed A, is a support, preferably in the form of angle arms C to which is adjustably secured the switch box D. To this end, the switch box is provided with lugs, or extensions d, to 110

receive bolts or other suitable attaching devices, the latter engaging the arms C and being adjustable laterally thereon by means of slots c. It will thus be seen that the 5 switch box and the switch contained therein, are adjustable laterally with reference to the bed A, so as to position the switch in either operative or inoperative position as desired.

- 10 The switch box D contains a switch E preferably of oscillatory type, and movable back and forth to control a resistance element, not shown, for varying the speed of the motor which drives the traveling work support. When the switch is in the vertical position illustrated in Figure 2 in dotted lines the table travels at a fast rate of speed, and when the switch is inclined to the vertical, as shown in Figures 1 and 3 the table 15 travels at a slow rate of speed, the position of the switch being determined by the controlling devices or dogs on the traveling work support, as now to be described.

The switch is provided at its upper and 20 lower ends with horizontally extending operating portions, or projections e, e' located in different horizontal planes, and the lower one projecting away from the switch farther than the upper one so that they terminate 25 in different vertical planes. Arranged on the traveling work support are pairs of dogs, as many as may be desired, and each pair comprises a short downwardly extending dog F, which engages the upper operating 30 portion e on the switch, and a longer downwardly extending dog F', which engages the lower operating portion e' on the switch. The lower end of the long dog F' is offset with reference to its upper portion, 35 so as to clear the upper operating portion e and engage the lower operating portion e', as shown in figure.

Each dog is pivotally mounted in a carrier G, adjustably arranged in a dove-tail slot H at the side of the traveling work support, and the dog, by reason of its pivotal connection is free to swing in one direction, 40 so as to ride over its operating portion of the switch during the return travel of the work support, and is held rigidly against 45 swinging movement in the opposite direction by the carrier G, so as to engage its operating portion of the switch and move the latter properly during the forward 50 travel of the work support.

The operation of the mechanism briefly is 55 as follows: The switch box D is adjusted outwardly to proper relationship with the dogs, and the controlling dogs are adjusted 60 on the work support, in accordance with the location of the parts of the work where operations are to be performed. Assuming 65 that the parts are in the position shown in Figure 2 in dotted lines the work support starts to travel forwardly and moves in this

direction at a fast rate of speed until the first dog F engages the operating portion e of the switch. This swings the switch over, cutting in the resistance and causing the work support to travel at a slower rate of 70 speed during the cutting operation. At the end of such cutting operation, the second dog F' of the pair engages the lower operating portion e' of the switch, swinging the latter in the opposite direction and returning it to its normal position. This cuts out the resistance element, and causes the work support to travel at a faster rate of speed until the next pair of dogs is encountered. This operation is repeated as many 75 times as there are pairs of dogs during the forward travel of the work support, and during its return movement, all the controlling dogs swing about their pivotal points, and ride over the operating portions of the 80 switch, so that the latter is not moved during the return travel of the work support, which is consequently driven at a constant 85 rate of speed until it again starts forwardly. If at any time it is desirable to temporarily 90 eliminate the speed changing mechanism, this is done by loosening the attaching devices for the switch box, and sliding the latter toward the bed A, until the switch 95 operating portions are out of the path of the controlling dogs on the work support.

I claim:

1. In a planer, the combination with a bed and an electrically driven work support traveling thereon, of an oscillatory resistance-controlling switch for varying the speed of the work support, said switch having mounted thereon oppositely arranged operating portions located in different horizontal planes, and dogs of different lengths 100 extending downwardly from the work support, the lower ends of said dogs cooperating 105 with said operating portions on the switch to move it first in one direction and then in the other.

2. In a planer, the combination with a bed and an electrically driven work support traveling thereon, of an oscillatory resistance-controlling switch for varying the speed of the work support, said switch having mounted thereon oppositely arranged operating portions located in different horizontal planes and terminating in different vertical planes, and dogs of different lengths 110 extending downwardly from the work support, the lower ends of the dogs being arranged in different vertical planes and co-operating with said operating portions on the switch to move it first in one direction and then in the other.

3. In a planer, the combination with a bed and an electrically driven work support traveling thereon, of an oscillatory resistance-controlling switch for varying the speed of the work support, said switch hav- 115 120 125 130

- ing mounted thereon oppositely arranged operating portions located in different horizontal planes and terminating in different vertical planes, dogs of different lengths extending downwardly from the work support, the lower ends of the dogs being arranged in different vertical planes and cooperating with said operating portions on the switch to move it first in one direction and then in the other, and supporting devices adjustably mounted on the work support, the dogs being pivoted on the supporting devices and retained against movement in one direction, whereby the dogs are free to ride over the operating portions of the switch without moving it during the return travel of the work support.
4. In a planer, the combination with a bed and an electrically driven work support traveling thereon, of a resistance-controlling switch for varying the speed of the work support, devices carried by the work support and cooperating with said switch, supports secured to the bed beneath said work support, and a switch box containing said switch and adjustable horizontally on said supports into and out of cooperative relationship with said devices.
5. In a planer, the combination with a bed and an electrically driven work support travelling thereon, of an oscillatory resistance controlling switch for varying the speed of the work, said switch having mounted thereon oppositely arranged operating portions located in different horizontal planes, dogs of different lengths extending downwardly from the work support, the lower ends of said dogs cooperating with the operating portions on the switch to move said switch first in one direction and then in the other, and a switch box containing said switch and adjustable on the bed to move the switch operating portions into or out of the path of said dogs.

In witness whereof, I have hereunto signed my name.

ALFRED TROSCH.
